UNITED STATES PATENT OFFICE.

J. WOOD PORTER, OF MORRIS, ILLINOIS.

PAPER-FOLDING MACHINE.

SPECIFICATION forming part of Letters Patent No. 364,293, dated June 7, 1887.

Application filed August 25, 1884. Renewed March 5, 1887. Serial No. 229,867. (No model.)

To all whom it may concern:

Be it known that I, J. WOOD PORTER, a citizen of the United States of America, residing at Morris, in the county of Grundy and State of Illinois, have invented certain new and useful Improvements in Paper-Folding Machines, of which the following is a specification, reference being had therein to the accompanying drawings.

10 Figure 1 is a plan view on the top. Fig. 2 is an edge view of the first table, P, looking at Fig. 1 in the direction of arrow 1, and a side view of the delivery-tapes and their supporting-pulleys, having an adjustable extending tape attachment, and showing that portion of a printing-press from which a paper is delivered to the machine. Fig. 3 is a side elevation of the machine, looking in the direction of arrow 1 of Fig. 1; Fig. 4, a side elevation of the 15 machine, looking in the direction of arrow 2 of Fig. 1. Fig. 5 is a side view of the receptacle into which the folded paper is delivered and its operating mechanism, having a portion of one side broken away, and a cross-section of 20 table P³ and compressing rolls y' y'; Fig. 6, a detailed view of a portion of Figs. 3 and 4, looking down from line x. Fig. 7 is a detailed sectional view of one of the turn-tables of one of the telescopic arms that operate the folding-blades, showing the manner in which the arm is pivoted to the frame of the machine. Fig. 25 8 is a side view of one of the telescopic arms detached from the machine, showing the manner in which it is attached to a folding-blade and pivoted to its operating drive-chain. Fig. 9 is a view of a telescopic arm, having portions broken away to show its interior construction; Fig. 10, a cross-sectional view of 30 one of the sections of one of the telescopic arms. Fig. 11 is a cross-sectional view of table P' and a portion of table P² and their adjacent and accompanying parts on line x' of Fig. 3. Fig. 12 is an edge view of table P³, looking in the direction of arrow 3, Fig. 1, and 35 a side view of a portion of a paper-receptacle for holding the folded paper, located immediately under said table. Fig. 13 is a perspective view of a single section of the paper-receptacle shown in Fig. 12. Fig. 14 is a top plan view 40 of one end of a paper-receptacle such as is shown in Fig. 5.

This invention relates to certain improve-

ments in paper-folding machines, and is designed to fold newspapers as they are printed and leave a printing-press, or for folding any 55 other kind of paper that may be desired, and whether delivered to it from a press or in any other manner. This machine is shown as arranged to make four folds in the paper, the folds being made by means of descending 60 blades secured to a traveling sprocket-chain, that strike the paper at the place where it is to be folded and carry it forward through a slot across the face of the table, on which it is delivered. The several tables are arranged in a 65 train with relation to each other and having their planes at right angles with each other, so that when a fold is made carrying the paper through a slot it is delivered on the face of the next succeeding slotted table for the 70 next fold to be made until all the folds are successively made and the paper delivered folded. The several folding-sections are substantially duplicates of each other, and may be multiplied to make as many folds as desired, and a 75 description of one of the folding-sections will suffice for all, or substantially so.

Referring to the drawings, A and A' constitute the skeleton frame which supports the operating parts, and are secured to each other 80 by the cross-bars B, B', and B², Figs. 1, 3, 4.

P, P', P², and P³ are the several slotted tables supported by said frame and cross-bars, upon which tables the paper to be folded comes in contact, or is spread.

85 The paper is first delivered from the cylinder of a printing-press by means of tapes v and v², Figs. 1 and 2. The respective tables are each provided with a slot, z, z', z², and z³, which extends from one side nearly across the 90 table, or as far as the paper to be folded is wide, and is located about the center of the table. The table P' stands vertically under table P, next to and at the side of slot z, so that when the folding-blade E carries the paper 95 folded through said slot it will deliver it against the face of table P', between it and the shields R R' and spring-clamps L' L'. Table P² stands vertically behind table P', with its plane at right angles with that of table P', as shown 100 more clearly in Fig. 11 and by the dotted lines in Fig. 3, so that when folding-blade E carries the paper, folded the second time, through slot z' of table P' it will deliver it against the

face of table P^2 , between it and shields $R^2 R^3$. Table P^3 lies horizontally behind vertical table P^2 , with its plane at right angles with that of table P^2 , as shown in Fig. 1, so that when folding-blade E^2 carries the paper, folded the third time, through slot z^2 in table P^2 it will deliver it on table P^3 . Folding-blade E^3 then descends and carries the paper, folded the fourth time, through the slot z^3 of table P^3 , between the pair of pressing-rollers $y' y'$, Figs. 5 and 12 and dotted lines Fig. 4, which rollers are secured to the under side of the table P^3 , and immediately over a receptacle into which the folded papers are deposited.

15 The slots through the several folding-tables are lined on either side by the thin spring-plates r and r' , curved, as shown, so they will not be caught by the operating parts. The inner edge of plate r is attached to the top of the table next the slot and its outer edge left free, while plate r' has each edge secured, one in the same manner as plate r and the other edge to the face of the next succeeding table through the slot, except, however, 20 in the case of table P^3 , where the outer edges of both spring-plates are left free, as shown in Figs. 5 and 12. These spring-plates serve to press slightly against the sides of the paper as it is being carried through the slots by the folding-blades, so as to hold the paper in place 25 while the folding is being done.

30 The outer ends of the slots in the respective tables are covered by a yoke. (Shown, respectively, at $t' t' t^2$ and t^3 .) These yokes serve to unite the two parts of the respective tables separated by the said slots, and also to guide the folding-blades more certainly into the slots.

35 The first table, P , is free on its upper surface, with the exception of the delivering-tapes v , while tables P' , P^2 , and P^3 are each respectively provided with shields $R R'$, $R^2 R^3$, and $R^4 R^5$, set a little distance from its respective table, as shown in Figs. 3, 4, and 11. These plates or shields are secured at their ends to the face 40 of the tables and serve to hold the paper folded between them and their respective tables after the folding-blades are withdrawn. The front edges of these shields are rounded, so as to prevent the paper or the folding-blades from 45 catching on them when the machine is backed.

50 S is a counter-shaft located at the upper part of the machine in boxes in frames $A A'$, and has rigidly secured thereto the chain-wheels W and W' and a sheave-wheel, b , and 55 is driven by chain c over chain-wheel W from a corresponding chain-wheel on the shaft of a printing-press.

55 S is the main shaft of the machine, and has rigidly secured on it the wheels K^2 , K^3 , K , and W^3 , and is rotated by chain c on chain-wheels W' and K^2 . Near the open slotted edge of each table is arranged an endless chain on suitable chain-wheels, having pivotally attached thereto a thin extending folding-blade, and 65 each such blade is attached to a telescopic arm, and each such arm is pivoted near its outer end to the frame of the machine. Each one

of the slotted tables is thus provided with a folding-blade, which is carried in a circuit by its drive-chain and caused to descend through the slot of its proper table to carry the paper forward and make a fold, and then withdraw from the fold in the paper. The sprocket-chain that operates the first folding-blade of the first folding-table, P , is shown at a' , Figs. 1 and 3, and is carried, as shown in Figs. 1 and 3, on sprocket-wheel D and the idler-wheels d and d' , and receives its motion from said wheel D , which is keyed on short shaft S^2 , boxed in frame A . Chain-wheel W^2 is also keyed to shaft S^2 at the inner side of said frame, and these said wheels are caused to rotate by means of chain c' on wheel W^2 of shaft S^2 and wheel W^3 of drive-shaft S . The chain a' travels in the direction of its accompanying arrow, and 80 has pivotally attached to it the folding-blade E , which travels with said chain a' . This blade is also attached to the outer end of the telescopic arm H , which is pivoted near its inner end to the frame A at J . When this folding-blade E commences its circuit, it is in a position similar to that of folding-blade E' , Fig. 4, and extends out over table P through the yoke to directly over slot z , and when in such position the telescopic arm H stands in 85 a perpendicular position, with its joint extended to reach that point, and will hold said folding-blade parallel with the upper face of said table P . When the chain a' travels, it will carry said folding-blade down through 90 said slot z and along the face of vertical folding-table P' , which stands next to said slot z , and between said table P' and the shields $R R'$, as shown in Fig. 3, until it has reached the base of said table P' and said shields, when its 95 point of attachment to said chain a' passes around idler-wheel d' , and said blade is withdrawn horizontally from between table P' and said shields $R R'$, and from the first fold it has made in the paper, by striking it about its center and carrying it folded once down through said slot and leaving it stand vertical between table P' and said shields $R R'$ and spring-clamps $L' L'$. (Shown in Fig. 3.) In said Fig. 3 the first folding-blade, E , just mentioned, is 100 shown as just having descended through slot z of table P and between vertical table P' and said shields, and about one-half its way down, as it would appear carrying a folded paper with it off of table P . The telescopic arm H 105 renders it possible for chain a' to carry blade E around the circuit described.

110 The next succeeding endless chain, a^2 , has attached to it the next folding-blade in order, E^2 , and is carried by the drive-wheel D^2 and 115 idler-wheels $d^4 d^5$, which are respectively boxed to cross-bars B and B' , and the folding-blade E^2 is attached to and conducted by said chain for the same purpose and in precisely the same manner as is folding-blade E , hereinbefore described. This folding-blade carries the paper with it, folded the second time, through slot z^2 of second table, P' , that stands vertically under table P , and leaves it between 120

the face of table P^2 and its shields $R^2 R^3$, and is then withdrawn, the same as blade E , by means of chain a^2 .

The mechanism that drives wheel D^2 is shown more fully in detail in Fig. 6 and by the dotted lines in Figs. 3 and 4.

e^4 is a shaft boxed to frame A and cross-bar B' , and has rigidly attached to it the wheel D^2 and a miter-gear, e' , which meshes into miter-gear e on shaft e^3 , which is bracketed to cross bar B' . On this shaft e^3 is keyed chain-wheel e^2 , which is driven by chain c^5 from said wheel e^2 and chain-wheel K on shaft S , Figs. 1 and 3. The next endless chain, a^3 , that is carried by the wheel D' and the two idler-wheel $d^2 d^3$, carries the third folding knife or blade, E^2 . This chain and said wheels are supported on the frame A^2 , (shown in Figs. 1, 4,) and which attaches to frame A' cross-bar B and secondary frame A^3 . This chain has attached to it the folding-blade E^2 , in the same manner as the other folding-blades are attached to the other chains described, and conducts said folding-blade through slot z^2 of table P^2 onto the horizontal surface of the last folding-table, P^3 , under the shields R^4 and R^5 , and is then withdrawn from the folded paper as the other folding-blades are, thus placing the third fold in the paper.

The mechanism that operates wheel D' is shown in Figs. 1 and 4. The drive-wheel D' and miter-gear x are keyed to a short shaft which is boxed in frame A^2 .

x^2 is a shaft boxed at one end in the frame A' and bracketed to frame A^2 at the other end, and has keyed thereon a miter-gear, x' , which meshes with miter-gear x , and is driven by chain c^3 on the said chain-wheel and chain-wheel W^1 on drive-shaft S , Fig. 1.

The next and last endless chain, a^4 , that has attached to it the last folding-blade, E^3 , is carried by drive-wheel D^3 and the idler-wheels $d^6 d^7$, which are attached to the secondary frame A^3 , which attaches at its ends to the cross-bars B and B^3 . Said chain conducts the folding-blade E^3 through slot z^3 in table P^3 , in the same manner as the other folding-blades are conducted through the slots in their respective tables, to carry the paper through it, and thus form the fourth fold in the paper.

The drive-wheel D^3 and chain-wheel K^3 are both keyed to a short shaft boxed in frame A^3 , and are driven by chain c^4 from chain-wheel K^3 on drive-shaft S . The telescopic arm H' , that carries folding-knife E' , is pivoted to cross-bar B at J' . (See Fig. 4.). Telescopic arm H^2 , that carries folding-blade E^2 , is pivoted to cross-bar B^2 at J^2 . Telescopic arm H^3 , that carries folding-blade E^3 , is pivoted to frame A^3 at J^3 , Fig. 3, and telescopic arm H , that carries folding-blade E , is pivoted at J to the frame A , Fig. 3.

The special construction of one of the telescopic arms is shown in Figs. 8, 9, and 10. H represents the barrel, into which the bar h' slides telescopically, and is provided with the stud m^2 , by means of which it pivots to the

frame of the machine. This barrel is square, as also is the end h' of rod h^2 , that slides in it, so that neither can rotate or permit the folding-blade E , attached rigidly to the bar h' , to sway from one side to the other, so it will not extend out indirectly over the slot in the table.

The barrel H is provided at its bottom with a cushion, i^2 , held therein by a pin, i' , to relieve the bar $h^2 h'$ from any jar when it descends to the bottom of the barrel. The barrel H is provided on its inner surface with a projection, i^3 , which engages with a similar projection, i^4 , on the bar $h^2 h'$, so it cannot pull out of the barrel H . The telescopic arm is attached to its chain a' by means of a sleeve, o' , which has on its side a wrist-pin that passes through the eye o^2 on one of the links of the chain. This sleeve o' is arranged to slide on the outer end of said bar or arm and impinges against the coil-spring h^4 , which has the tendency to hold the sleeve o' out toward the outer end of the arm or bar h^2 . The spring also permits the sleeve o' to be more readily conveyed in its circuit with the chain to which it attaches and turn around the wheels that bear the chain more readily than if it were rigidly fixed to the bar. Fig. 7 shows the manner in which the telescopic arm attaches to the frame A , m' being a seat, fastened to the frame A by means of the screw-bolts m^3 , forming a wide flat surface for the circular plate J'' (which is integral with stud m^2) to rest on and form a bearing that prevents any rolling of the telescopic arm. After the paper has received its last fold by being carried through slot z^3 of table P^3 , Fig. 12, it is passed between a pair of compressing-rollers, $y^1 y^2$, to compress its folds, and is then deposited in the receptacle for holding the folded papers until they can be removed. This receptacle is shown in Figs. 13, 3, 4, and 12, and is constructed as follows:

B^8 is an endless chain mounted on suitable rollers at each end, one of which is shown at T' , Fig. 12, which rollers may be bracketed to the frame of the machine, the upper one directly under the slot z^3 of the last folding-table, P^3 , as shown in said figure. To each link of said chain is attached a cross-bar, B^9 , Fig. 13, terminating at each end in the upturned points or arms B^{10} , and held in proper position and at the right distance apart by the strap-belts B^7 , as shown at Fig. 13.

One end of roller T' is furnished with a ratchet-wheel, B^4 , which turns roller T' , with the chain B^8 , intermittently, by means of the pawl B^5 , which is operated by and attached to crank-pin b^5 of disk b^6 on shaft e^4 , that receives its motion from the machine, as shown in Figs. 3, 4, 6, and 12. When the folded papers drop from between the rollers $y^1 y^2$, they fall between these arms B^{10} , which stand wide apart at that place, as shown in Fig. 12, as they pass around shaft T' . The ratchet B^4 intermittently rotates the chain B^8 with these arms B^{10} , so that every time a paper drops it will drop between the next succeeding pair of arms until they are all full, and can be removed by the operator, at

will, without stopping the machine, and is intended to be used when the folder is attached to a large and rapid printing-press, where it is not practicable to stop the press to remove the folded papers; but when the folder is used in connection with a small and slow printing-press, and where it is practicable to stop, a smaller and more simple receptacle is used, such as is shown in Figs. 5 and 14.

10 Referring to said figures, N is a trough, located immediately under the folding-table P³, so its slots y² y² at one end will be exactly under the rolls y' y' of said table, so the folded papers may fall in said trough from said rolls.

15 u is a movable or sliding head having a slide, u⁶, attached to its bottom and passing through a slot in the bottom of said trough N. This slide u⁶ has an opening in its lower end and arranged to ride or slide on a bar, u⁴, which 20 is bracketed to the bottom of trough N. A coil-spring, u⁵, on bar u⁴ presses against slide u⁶, forming a flexible backing for the sliding head u, and a spring-latch, u⁶, attached to head u and arranged to engage with the ratchet-teeth u⁹, holds the head u from being pressed 25 forward by said spring. A plunger, u², having the head u' attached to a crank-pin on chain-wheel x', which is bracketed to the machine, reciprocates said head u' back and forth past the slots y² y², and at each such forward movement takes a folded paper from said slots y² y² and deposits it against head u'. The lugs u³ prevent the return of the paper with the said plunger. Chain-wheel x' is rotated 30 by a chain from chain-wheel f, placed on shaft e⁴ (in place of disk b⁶). As papers accumulate the head u is pushed back and so held by the spring-catch u⁸. Each telescopic arm is so constructed that when their folding-blades 35 have passed through their respective slots and traveled along the surface of their respective tables, and the papers they have folded have been conducted far enough for the next succeeding fold to be made, and before their 40 pivoted connections with their respective traveling chains have reached a point where they pass around the second idler-wheel, the said arms will be completely telescoped and their sections be cushioned on their respective 45 cushions i², Fig. 9; and in order that said pivoted connections with said chains may pass around said last idler-wheel the sleeves o' will slide along on their respective bars and permit such passage, the springs h⁴ returning 50 said sleeves as soon as such point is passed, thus arresting the folding-blades when they have done their work and causing them to be withdrawn. When the folding-blades are 55 withdrawn from the fold in the paper, the telescopic bar or arm to which they attach will slightly elevate the outer end of the folding-blades to raise it directly up off of the paper before it is withdrawn, so it will not injure or 60 pull it out. The folding-knives are attached

to the telescopic arms by means of the slotted plate F, (shown in Figs. 3 and 8,) by means of proper set-bolts passing through said slots. This mode of attachment permits the vertical adjustment of the folding-blades to accommodate them to different-sized sheets of paper to 70 be folded. When the paper to be folded is small, the folding-blades may be set farther up, so as not to descend as far as when the sheet is large.

The arrangement of the tapes for delivering 75 the paper from a press to the folder is shown in Fig. 2. The tapes v on table P are placed on pulleys v' v'', and may continue on to pulley v², or separate tapes may be used from pulley v² each way, as may be desired. 80 Pulley v² is supported by arm m, attached to plate y, to extend out from the table P. Arm m is made adjustable by means of slot n' in its inner end, and held in any desired position by set-screws n in plate y, to adapt the tape to 85 a press of any height. Secondary tapes v³ are arranged on suitable pulleys above tape v, so the paper may be taken in between said tapes as it is delivered from the tapes of a printing-press from the cylinder G and rolls 1, 2, and 90 3. Stops T T (shown in Fig. 3) stop the paper when it reaches its proper position on table P. As soon as a paper leaves table P another may at once be delivered on it, so several papers may be in the process of being 95 folded at once.

Having thus described my invention, what I claim as new, and desire to secure by Letters Patent, is as follows, to wit:

1. In a paper-folding machine, a series of 100 folding-blades pivotally attached to a series of endless traveling chains mounted on suitable wheels and properly guided by a series of pivoted telescopic arms, in combination with a series of slotted folding-tables, constructed 105 and arranged substantially as shown, said blades being adapted to fold a paper in the manner substantially as set forth.

2. In the paper-folding machine described, the sleeves o', in combination with the telescopic arms described, having the coil-springs h⁴, endless chains a' a² a³ a⁴, and the folding-blades E E' E² E³, as and for the purpose set forth.

3. In the paper-folding machine described, 115 the combination of the slotted tables described, having the shields described, with the spring-clamps L' L', as and for the purpose set forth.

4. The combination of frame A A', shaft S², wheel D, chain a', idler-wheels d d', telescopic 120 arm H, folding-blade E, table P, having the slot z, and the means described for operating said parts, as and for the purpose set forth.

J. WOOD PORTER.
